Primary Examiner — Darlington Ly**(74) Attorney, Agent, or Firm** — Plumsea Law Group, LLC(57) **CLAIM**

The ornamental design for a display screen with icon, as shown and described.

DESCRIPTION

[The sole FIGURE] FIG. 1 is a front view of a first embodiment of a display screen with icon, showing the new design [ ]; and,

FIG. 2 is a front view of a second embodiment of a display screen with icon showing the new design.

The broken lines of uneven length show the display screen and form no part of the claimed design.

1 Claim, 2 Drawing Sheets

Matter enclosed in heavy brackets [ ] appears in the original patent but forms no part of this reissue; matter printed in italics indicates the additions made by reissue.
